UNITED STATES PATENT OFFICE.

ALLEN CLAY WHITEMAN, OF LA CROSSE, KANSAS.

LACING DEVICE.

1,393,188.

Specification of Letters Patent.

Patented Oct. 11, 1921.

Application filed May 24, 1921. Serial No. 472,089.

To all whom it may concern:

Be it known that I, ALLEN CLAY WHITEMAN, a citizen of the United States, residing at La Crosse, in the county of Rush and 5 State of Kansas, have invented a new and useful Lacing Device, of which the following is a specification.

It is the object of this invention to provide a simple but effective means whereby 10 the wings of a corset, glove, shoe or other article may be drawn together readily, means being provided whereby the flexible element or lace will be mounted anti-frictionally, the construction being such that 15 the lace will not become detached from the article.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:—

Figure 1 shows in front elevation, a device constructed in accordance with the invention; Fig. 2 is a section on the line 2—2 of 35 Fig. 1; and Fig. 3 is an elevation showing one of the pulleys.

In Fig. 1, the numeral 1 denotes the wings or sides of a shoe, glove, corset or other article, one wing having a tongue, 40 ordinarily, the tongue 2 overlapping the other wing. Oppositely disposed guides 3 are mounted on the wings 1. Each guide is composed on an inner plate 4 and an outer plate 5, the inner plate 4 bearing against the

wing 1. Securing elements 6 pass through 45 the plates 4 and 5. The securing elements 6 have heads 7 engaging the outer plate 5 and may be provided at their inner ends with prongs 8 engaging the part 1, the securing elements passing through the said 50 part 1. On each securing element 6, a pulley 9 is journaled, the pulleys being located between the plates 4 and 5. Each pulley has a grooved thread 10, provided with transverse ribs 11. 55

A flexible element is extended as shown at 18 in Fig. 1 between the lowermost guides 3, and passes between the pulleys 9 of the said guides. The flexible element is crossed on itself, as indicated at 14, as it extends 60 upward, and is prolonged between the pulleys 9 of each guide 3. The upper free ends 15 of the flexible element may be tied together or secured otherwise.

In practical operation, the wings 1 may 65 be separated readily, since the flexible element is carried anti-frictionally by the pulleys 9. The ribs 11 enhance the hold of the flexible element on the pulleys and secure a rotation of the pulleys, as distinguished 70 from a sliding movement of the flexible element.

I claim:—

In a device of the class described, co-operating wings; guides disposed upon the 75 wings, each guide embodying pulleys having grooved treads provided with transverse ribs; and a flexible element extended between the pulleys of each guide and co-operating with the threads and the ribs 80 thereof.

In testimony that I claim the foregoing as my own, I have hereto affixed my signature in the presence of two witnesses.

ALLEN CLAY WHITEMAN.

Witnesses:

HARRY T. FISH,
M. M. WILSON.
